FLUID COOLING APPARATUS

Frederick L. Shelor, Richmond, Va., assignor to
 S. & S. Engineering Corporation, Richmond, Va.,
 a corporation of Virginia

Application January 3, 1933, Serial No. 649,997

12 Claims. (Cl. 62—154)

The invention relates to new and useful improvements in a fluid cooler which may be used for cooling the temperature of a room, or which may be used for cooling drinking water, or for other purposes.

Prior to my invention, fluid coolers have been provided wherein a current of air is passed over an absorbent material saturated with water. The absorbent material is placed on the outer surface of a receptacle and water from the receptacle is applied thereto through a wick leading into the receptacle. One of the great disadvantages of an apparatus of this character resides in the fact that when the air current is cut off for any reason, the means for supplying water to the absorbent material continues to function, resulting in the objectionable dripping of water therefrom.

An object of the present invention is to provide a fluid cooler wherein the air current flowing across the vaporizing surface of the cooler may be stopped and the supply of water to the vaporizing surface also stopped.

A further object of the invention is to provide an apparatus of the above character with means for continuously supplying the receptacle with water, so that the supply in the receptacle is maintained at a predetermined level.

A further object of the invention is to provide an apparatus of the above character wherein a fan may be used for generating an air current, which fan is placed below the receptacle, and wherein means is provided for atomizing any fluid collecting at the bottom of the receptacle and dripping on to the central portion of the fan.

A still further object of the invention is to provide an apparatus of the above type wherein a baffle is arranged so as to provide a relatively long path of travel for the air current over the vaporizing surface.

These and other objects will in part be obvious and will in part be hereinafter more fully disclosed.

In the drawing—

Figure 1 is a view partly in side elevation and partly in vertical section showing an apparatus embodying the improvements as applied to the cooling of the air in a room;

Fig. 2 is a sectional view on the line 2—2 of Fig. 1;

Fig. 3 is an enlarged view, showing partly in section and partly in side elevation, the construction of the receptacle for the water and the manner of raising and lowering the same for varying the supply of water to the absorbent material on the outer face thereof; and

Fig. 4 is a vertical sectional view showing a portion only of the apparatus modified so as to cool drinking water.

The invention is directed to a fluid cooling apparatus which may be used for cooling the air of a room, or which may, with slight changes, be used for cooling drinking water. Said apparatus includes a receptacle which is supplied with water in such a way as to maintain a predetermined level of water. The receptacle is liquid-tight, and may be made of metal or any other suitable impervious material. On the outer face of the receptacle is an absorbent material which may be of any desired character which will absorb water and distribute the same so that it may be quickly vaporized. This material is supplied with water from the receptacle in any suitable way, and means is provided for varying the amount of water supplied thereto and for cutting off entirely the supply of water, when desired. Surrounding the receptacle and spaced thereto is a casing for directing the air current over the vaporizing surface. When the apparatus is used for cooling a room, the air in the room is caused to circulate through the casing and contact with the vaporizing surface. The vaporizing of the water will cool the air. When it is desired to use the apparatus for cooling drinking water, then a suitable supply pipe and spigot is provided which leads from the inner receptacle to a point outside of the casing. The converting of the water on the surface of the absorbent material into a vapor not only takes heat from the air current flowing over the surface of the absorbent material, but also heat from the receptacle and the water therein.

Referring more in detail to the drawing, the invention is embodied in an apparatus which is provided with an inner receptacle 1 preferably of metal, and which, as shown in the drawing, is in general, cylindrical. The wall of the receptacle, however, throughout a greater portion of its extent, at least, is corrugated, thus forming inwardly curved sections 1^a with outwardly curved sections 1^b therebetween. Located in the recesses 100 formed by the inwardly curved portions 1^a are fibrous cords 2 which extend preferably from the top of the receptacle to the bottom thereof. Surrounding the fibrous cords and the receptacle is a wire mesh cylinder 3 which also extends from the top to the bottom of the receptacle. The collar 4 may be placed around the wire mesh cylinder for firmly clamping the same against the outwardly curved portions 1^b of the cylinder, and also against the fibrous cords. This secures the 110

fibrous cords to the receptacle so that they remain fixed thereto, as a unit. The inwardly curved portions 1^a are provided with a series of openings 5 arranged in a line substantially parallel with the bottom face of the receptacle. There is also a series of openings 7 located above the openings 5.

Surrounding this receptacle 1 is a casing 9. The casing is attached to a supporting base 10 which is provided with openings 11, 11 covered by a suitable screen. Located within the base 10 of the casing is a motor 12 carrying a fan 13. Surrounding the fan is a sleeve 14 which is attached to the casing at intervals so as to provide a space 15 between the sleeve and the casing. Attached to the fan and rotating therewith is a funnel-shaped receptacle 16.

Located above the fan is a shaft 17 extending horizontally through the casing and mounted in suitable bearings therein. On the outer end of this shaft is a handle 18 whereby it may be turned at will. Carried by the shaft is a supporting member 19 having a flat face 20 relatively close to the shaft 17 and a flat face 21 at a relatively remote distance therefrom. There are also flat faces 22 and 23 which are radially nearer the shaft than the face 21. The receptacle 1 rests on this supporting member 19. When said supporting member is in the full line position shown in Fig. 3, the receptacle is in its lowest position in the casing. When the shaft is turned so as to place the supporting member 19 in the broken line position, it will raise the receptacle to the dotted line position in said Figure 3. If the shaft 17 is turned so as to bring the flat face 21 beneath the receptacle, it will be raised to a still higher position.

Means is provided for supplying the receptacle 1 with water. In the present illustrated embodiment of the invention, the casing 9 is shaped so as to provide a supporting bracket 25 carrying a supporting member 26 having a seat 27 to receive the neck of a bottle 28 which is inverted so as to project down through said seat. The bottle neck extends down into the receptacle and supplies the receptacle with water. The bottle has a fixed relation to the casing and will provide in said receptacle a water level having a fixed position relative to the casing. This water level is indicated by the broken line 24 in Fig. 3. The water level is not changed, but the receptacle may be raised and lowered relative to this water level. When in its lowest position, as shown in Fig. 3, the water level will be above the upper line of openings 7 so that both lines of openings 5 and 7 are beneath the water level. Water will pass out through these openings, and contacting with the fibrous cords, will saturate said cords with water, thus forming on the surfaces of the cords water films. When the shaft 17 is rotated to the dotted line position shown in Fig. 3, then the surface 22 will take the position indicated at 22a, and the receptacle will be raised so that the openings 7 will be lifted to the dotted line position indicated at 7a, while the openings 5 will be lifted to the position of the openings 7. In this position of the receptacle, only the openings 5 will be beneath the water level and supplying water to the fibrous cords. When the shaft 17 is rotated so as to support the receptacle on the surface 21 of the supporting member 19, then the opening 5 will be raised above the water level and the supply of water to the fibrous cords cut off. It will be understood, of course, that any number of rows of openings

may be provided, and thus the amount of water supplied to the fibrous cords varied at will, or cut off entirely, whenever it is desired to render the apparatus inoperative.

Surrounding the bottle is a casing 29 having suitable louvers 30 therein. There are also ports 31 in the supporting member 26. The casing 9 is spaced from the receptacle as noted above, and a spirally laid baffle plate 32 is disposed between the casing and the receptacle so as to provide a circuitous path for the air about the receptacle. When the motor is connected to its operating circuit, the fan will cause a current of air to flow through this circuitous path between the receptacle and the casing and to pass on up through the ports 31 and out through the louvers 30. The air will pass into the wire mesh cylinder and cause more or less of a turbulence, thus insuring that the air will contact with the water film on the cords, giving up heat thereto for the vaporization of the water. This will cool the air; it will also cool the wall of the receptacle, and the water within the receptacle. The cooled air passes on up and out through the louvers 30, and will circulate through the room and pass in again through the openings 11. When it is desired to stop the circulation of the air, it is very essential that the water supply to the fibrous cords be cut off, otherwise the water will pass out through the openings and drip from the cords into the base 105 of the receptacle. Therefore, when the motor is to be shut off, the handle 18 is turned so as to raise all of the apertures above the water level, determined by the position of the bottle neck in the casing. If it is desired to supply the air 110 with less water to be vaporized, then the receptacle can be raised a less distance and cut off a portion of the water supply.

The purpose of the wire mesh cylinder is, of course, to retain the fibrous cords in place, and also to break the air current passing over the same. Instead of fibrous cords, it will be understood that the absorbent material for the water may be in any suitable form so as to provide a water film on the surface thereof over which the air currents pass. The specific form shown is purely for the purpose of illustrating one embodiment of the invention. The fibrous cords may be of wicking or woven fabric, or any other similar material. The cords, likewise, may be made of other material, such as unglazed earthen ware. The essential feature consists in providing some sort of absorbent material which can be charged or supplied with water from the inner receptacle, and which will become saturated 120 so as to produce a film of water on its surface over which the air currents may pass.

The purpose of the funnel carried by and rotating with the fan is to catch any water which may accumulate and drip from the lower end of the cords. The water dropping into the funnel will be thrown by centrifugal force in the form of a spray off from the edge of the funnel and will be taken up by the air currents passing upwardly through the casing. The water accumulating on the inner surface of the casing may pass down through the openings 15 between the sleeve surrounding the fan and the wall of the casing.

In Fig. 4 of the drawing, there is shown an attachment for supplying cool drinking water. This is accomplished by a pipe 33 which extends into the receptacle 1 and out through the wall thereof, there being a watertight connection between the pipe and the wall of the receptacle. 145

This pipe projects through a slot in the casing 1 and attached to the end thereof is a spigot 34. Attached to the casing is a bracket 35 on which the drinking cup 36 may be placed. The purpose of 5 the slot in the casing is to permit the receptacle 1 to be raised and lowered as described above. The heat absorbed by the vaporization of the water will be taken from the wall of the receptacle, and the water within the receptacle, thus 10 cooling the same.

It is obvious that changes in the details of construction and the arrangement of the parts may be made without departing from the spirit of the invention as set forth in the appended claims.

15 Having thus described the invention, what I claim as new and desire to secure by Letters Patent, is—

1. A fluid cooler comprising a liquid-tight receptacle, means for maintaining a predetermined level of water therein, an absorbent material on 20 the exterior of said receptacle, communicating means for supplying water from the receptacle to said absorbent material for saturating the same, means for directing a current of air over the surface of the absorbent material for vaporizing the water thereon, and means whereby said communicating means may be shifted at will relative to the level of the water whereby the supply of water to the absorbent material may be 25 stopped.

2. A fluid cooler comprising a liquid-tight receptacle, means for maintaining a predetermined level of water therein, an absorbent material on 30 the exterior of said receptacle, communicating means for supplying water from the receptacle to said absorbent material for saturating the same, a casing surrounding said receptacle and forming an air passage therebetween, a motor at the lower end of the receptacle for forcibly 35 directing the current of air through the passage and over the surface of the absorbent material for vaporizing the water thereon, and means whereby said communicating means may be shifted at will relative to the level of the water whereby the supply of water to the absorbent material may be stopped.

3. A fluid cooler comprising a liquid-tight receptacle, means for maintaining a predetermined level of water therein, an absorbent material on 40 the exterior of said receptacle, communicating means for supplying water from the receptacle to said absorbent material for saturating the same, a casing surrounding said receptacle and forming an air passage therebetween, a spiral baffle 45 between the casing and receptacle for producing a circuitous passage for the air, a motor driven fan at the lower end of the receptacle for forcibly supplying an air current through said passage for vaporizing the water thereon, and means whereby said communicating means may be shifted at will relative to the level of the water whereby the supply of water to the absorbent material may be stopped.

4. A fluid cooler comprising a liquid-tight receptacle, means for maintaining a supply of water 45 therein, an absorbent material on the exterior of said receptacle, means for supplying water from the receptacle to said absorbent material for saturating the same, a motor driven fan at the 50 lower end of the receptacle for directing a current of air over the surface of the absorbent material for vaporizing the water thereon, and means whereby the supply of water to the absorbent material may be stopped when the motor 55 is stopped.

5. A fluid cooler comprising a liquid-tight receptacle, a casing surrounding said receptacle and spaced therefrom, a support carried by the casing above the receptacle on which a water supplying receptacle may be supported for feeding water to the receptacle and maintaining a predetermined level of water, an absorbent material on the outer surface of said receptacle, means whereby said absorbent material may, at will, be caused to contact with the water in the receptacle or removed from contact therewith, and a motor-driven fan at the lower end of the said receptacle for driving an air current over the absorbent material.

6. A fluid cooler comprising a liquid-tight receptacle, a casing surrounding said receptacle and spaced therefrom, means for maintaining the supply of water in said receptacle having a predetermined level relative to the casing, an absorbent material on the exterior of said casing, a series of openings in the wall of said receptacle through which water may be supplied from the receptacle to said absorbent material, and means whereby the receptacle may be raised and lowered for positioning said openings above or below the predetermined water level for varying the supply of water to said absorbent material or for cutting off entirely the supply thereto.

7. A fluid cooler comprising a liquid-tight receptacle, a casing surrounding said receptacle and spaced therefrom, means for maintaining the supply of water in said receptacle having a predetermined level relative to the casing, an absorbent material on the exterior of said receptacle, and means whereby water may be supplied to said absorbent material from said receptacle and the supply of water varied or cut off at will.

8. A fluid cooler comprising a liquid-tight receptacle having the wall thereof formed with inwardly curved portions extending vertically of the receptacle, and forming recesses on the outer face thereof, absorbent material in said recesses, the wall of said receptacle having lines of openings at different levels adjacent the upper end of the receptacle leading from the interior of the receptacle to said recesses for supplying water from the receptacle to the absorbent material, a casing surrounding said receptacle, means for maintaining a supply of water in said receptacle having a predetermined water level of a fixed height relative to said casing, and means for raising and lowering said receptacle in said casing for varying the position of the opening relative to the water level whereby the supply of water to the absorbent material may be varied or cut off at will.

9. A fluid cooler comprising a liquid-tight receptacle having the wall thereof formed with inwardly curved portions extending vertically of the receptacle, and forming recesses on the outer face thereof, absorbent material in said recesses, the wall of said receptacle having lines of openings at different levels adjacent the upper end of the receptacle leading from the interior of the receptacle to said recesses for supplying water from the receptacle to the absorbent material, a wire mesh cylinder surrounding said receptacle and contacting with the absorbent material in said recesses, a casing surrounding said receptacle, means for maintaining a supply of water in said receptacle having a predetermined water level of a fixed height relative to said casing, and means for raising and lowering said receptacle in said casing for varying the position of the openings relative to the water level whereby the supply

of water to the absorbent material may be varied or cut off at will.

10. A fluid cooler comprising a liquid-tight receptacle having the wall thereof formed with inwardly curved portions extending vertically of the receptacle, and forming recesses on the outer face thereof, absorbent material in said recesses, the wall of said receptacle having lines of openings at different levels adjacent the upper end of the receptacle leading from the interior of the receptacle to said recesses for supplying water from the receptacle to the absorbent material, a casing surrounding said receptacle, means for maintaining a supply of water in said receptacle having a predetermined water level of a fixed height relative to said casing, means for raising and lowering said receptacle in said casing for varying the position of the openings relative to the water level whereby the supply of water to the absorbent material may be varied or cut off at will, said casing being spaced from said receptacle and having a baffle plate therein for directing an air current over the surface of the absorbent material, and a motor driven fan in said casing beneath said receptacle, said fan having a funnel receptacle rotating therewith and disposed beneath the first-named receptacle for collecting and vaporizing the water dropping from the absorbent material.
15. A fluid cooler comprising a liquid-tight receptacle having a predetermined water level of a fixed height relative to said casing, and means for raising and lowering said receptacle in said casing for varying the position of the openings relative to the water level whereby the supply of water to the absorbent material may be varied or cut off at will, said casing being spaced from said receptacle and having a baffle plate therein for directing an air current over the surface of the absorbent material, and a motor driven fan in said casing beneath said receptacle.
20. A fluid cooler comprising a liquid-tight receptacle having the wall thereof formed with inwardly curved portions extending vertically of the receptacle, and forming recesses on the outer face thereof, absorbent material in said recesses, the wall of said receptacle having lines of openings at different levels adjacent the upper end
